FISH GRIPPER

George F. May, 121 S. Briscoe St., Dallas, Tex. 75211,
and Clifford T. Calfee, 2710 National Drive, Garland,
Tex. 75041

Filed Oct. 24, 1972, Ser. No. 299,790

Term of patent 14 years

Int. Cl. D22—05

U.S. Cl. D22—31

FIG. 1

FIG. 4

FIG. 2

FIG. 3

FIG. 5

FIG. 6

FIG. 1 is a perspective view of a fish gripper showing our new design;

FIG. 2 is a front elevational view thereof, the rear being a mirror image;

FIG. 3 is a left end view of FIG. 2;

FIG. 4 is a right end view of FIG. 2;

FIG. 5 is a top plan view thereof; and

FIG. 6 is a bottom plan view thereof.

We claim:

The ornamental design for a fish gripper, as shown and described.
